WEB SUPPLY MECHANISM FOR PRINTING MACHINES

Hermann Hezel, New York, N. Y., assignor to Irving Trust Company, temporary trustee for R. Hoe & Co., Inc., New York, N. Y., a corporation of New York

Application July 5, 1933, Serial No. 679,028

15 Claims. (Cl. 242—58)

This invention relates in general to web supply mechanism, such as is used for printing machines, and more particularly to improved means for severing adhesive tape or tabs and the like pasted 5 to and temporarily joining the free end of a replacement roll to the body portion thereof preparatory to making a non-stop join of a web of a replacement roll to a web running from an expiring web roll.

10 The object of the invention is to provide an improved device of the general character illustrated in pending applications of Tomlin et al., Serial Nos. 578,270 and 596,508, filed December 1, 1931 and March 3, 1932 for Method and means 15 for renewing webs of printing machines, and for Improvements in web supply mechanism, respectively.

It is also an object of the invention to provide improved means for temporarily attaching the 20 free end of a web roll to the body portion thereof preparatory to severing same, of generally improved construction, whereby the device will be simple, durable and inexpensive in construction, as well as convenient, practical, serviceable and 25 efficient in its use.

With the foregoing and other objects in view, which will appear as the description proceeds, the invention resides in the combination and arrangement of parts, and in the details of construction hereinafter described and claimed.

30 The preferred embodiment of the invention is illustrated in the accompanying drawings wherein:

Figure 1 is a fragmentary end elevational view 35 of a web roll supporting mechanism to which the present improved means for securing and severing tabs and the like on the end and an adjacent body portion of a replacement roll, is secured;

40 Figure 2 is a side elevational view, partly in section, of one of the devices embodying the invention, illustrating the positions of the device before and after the severing of the adhesive straps which temporarily bind the free end of the 45 replacement roll to the body portion; certain parts of the adjacent roll supporting mechanism being shown in section and partly in elevation;

Figure 3 is a fragmentary elevational view of the device shown in Figure 2;

50 Figure 4 is an enlarged plan view of the device as viewed in the direction of the arrow 4 of Figure 3, showing the web end securing tapes operatively secured to the device, and the relative 55 position of associated adjacent parts prior to actuation of the knife;

Figure 5 is a view similar to Figure 4, showing the knife blade moved to a position where it has severed the tapes;

Figure 6 is an enlarged fragmentary side elevational view of the device showing the parts 5 in the same relative position as in Figure 4; and

Figure 7 is a fragmentary plan view as seen on the line and as viewed in the direction of the arrow 7 of Figure 2.

With more particular reference to the drawings wherein similar characters of reference indicate corresponding parts in the several views of the preferred form of the invention, 10 designates a column of a web roll supply mechanism which may form a part of the support or frame 15 of a printing machine, and 11, 11' a base and girder respectively, between which the column 10 is arranged. A web roll supporting member or reel 12 is provided with roll engaging spindles or cones 13 rotatable relatively to a fixed support 20 hereinafter described and adapted to engage the cores of a pair of web rolls mounted thereon; i. e., a fresh or replacement web roll 14 and an exhausting web roll 15, it being understood that as customary the reel 12 may be swung or rotated 25 about its axis to bring each of the web rolls 14, 15 in turn into desired positions for feeding, loading, web renewal, etc.

In a manner similar to that described in the above-mentioned applications of Tomlin et al., a 30 pair of adhesive tabs or binder straps 16, 17 are provided which serve to confine the free end of the replacement web roll 14 to the body portion 35 at either side thereof, and which are arranged in transverse or crossing relation to each other at the sides of the web roll and in overlapping relation to same, one of the said straps 16 being pasted to a diagonally or helically stretching portion of the free end of the replacement web roll, while the other strap 17 is pasted on the body 40 portion of the last mentioned web roll and passed under or over the strap 16.

Novel means for engaging the binder straps 16, 17 and severing same at a predetermined time are provided, the said means including a pair of 45 similar members or strap anchors 18, which are freely rotatable on the pair of cones or spindles 13 supporting the replacement web roll 14 at either end. The details of the member 18 are fully described in the above-referred Tomlin et al. 50 application, Serial No. 596,508, and form no part of the present mechanism.

In accordance with the present invention, each 55 of the said strap members 18 includes an annular member 19 which is fastened by screws 21 to a

ratchet plate 22, the annular member 19 being formed of two semi-circular sections 23, 24 joined by screws 25, and providing, when joined together, a pair of holes 26 spaced 180° apart, only one 5 of which is shown, in which studs or trunnions 27 formed on a collar or ring 28 are inserted. The studs 27 permit the swinging or rocking of the strap anchors in a plane transverse to that of the axis of the replacement roll 14, for a purpose 10 which will appear hereinafter. The annular member 19 encircles the collar 28 which rotates about the axis of the adjacent cone 13 and is secured to an inner ring 29 arranged on the cone 13 and engaged against a second ring 31 fastened 15 to a retainer ring 32. A bearing 33 is arranged on a reduced portion of the fixed support alluded to above and hereinafter described, between two washers 34, 35 and the rings 29, 32, the ring 29 being provided with an annular groove 36 on its 20 inner surface, the said groove receiving packing or other lubricant retaining material 37. The ring 29 is also provided with a pocket 38, accommodating an inner end or portion of a spring 39, the outer end of which is received in a coacting 25 pocket 41 formed in the lateral surface of the annular member 19, it being understood that the annular member 19 and the ring 29 rotate in unison. The elements 31-35 inclusive are encircled by casing 42 which is fastened to a bracket 30 43 fixed to a non-rotatable shaft 44 which is the fixed support alluded to above. The strap anchors 18 and associated parts including the elements 28-32, it is understood rotate in unison relatively to the fixed support as the replacement 35 roll rotates, preparatory to joining the web of the latter to the web of the expiring roll until the "flying paster" is accomplished, after which the said strap anchors and their component parts are freed from the end of the web 40 of the replacement web roll by the severing of the binder straps 16, 17, as hereinafter described, and brought to a stop.

By further inspection of Figure 2, it will be seen that a recess 45 is formed in the inner lateral face of the element 42. The said recess 45 is adapted to receive a lug or tongue 46 fastened to the ratchet arm 22 when the latter and consequently the strap binder anchor head indicated generally at 47, to which it is attached and having the binder strap engaging elements 48 thereon, is tilted by the action of spring 39. This tilting of the anchor head 47 occurs when the binder straps are severed by the knife 49 of the said anchor head, thus freeing or releasing the latter 50 from the replacement web roll 14, at the moment when the free end of the web of the replacement web roll is joined to the traveling web of the expiring roll. As the now released and spring biased ratchet plate 22 to which the anchor head 55 47 is fastened, swings past the recess 45, the tongue 46 will enter the said recess 45 and thereby lock the ratchet plate 22 and associated parts including the anchor head 47 to the fixed member or shaft 44, consequently allowing the web of the 60 replacement web roll to feed unimpeded to the printing machine.

The operation of the device may now be summarized as follows:

In accordance with the above-referred to applications of Tomlin et al., Nos. 578,270 and 70 596,508, a pair of the binder tapes or straps 16, 17, having their outer surface smeared with an adhesive, are attached or pasted to the free end of the web of the replacement roll and the body 75 portion at each side thereof and are secured to

one of the web binder anchors or heads 47 after being passed through the slot 51 provided in the latter, thus anchoring the said straps operatively to the replacement roll 14 in the position best shown in Figure 2, it being understood that two web binder anchors 47, one at each end of the replacement web roll 14 for an adjacent pair of binder straps, are provided.

It will now be understood when the replacement web roll 14 is rotated by an endless belt 10 assembly secured to the frame 10 and indicated generally at 52, the binder straps 16, 17, fastened to the free end of the said replacement roll and to the binder arms, will serve to rotate the latter with the roll. At a predetermined time, after the peripheral speed of the replacement roll which has been swung previously to the position shown in Figure 1, is equal to that of the traveling web of the expiring roll 15, a brush arm or web deflector 53, described in application No. 20 578,270 above referred to, is swung against the traveling web of the latter, thereby thrusting same against the adhesive smeared outer surface of the helically positioned straps which are pasted on their inner surface to the free end of the 25 replacement roll. The projecting trigger 54 on the strap anchoring member 47, which is operatively connected to the knife 49, will now strike against an abutting lower surface of the web deflector 53, thereby actuating or swinging the said 30 knife 49 through the slot 51 thus severing the binder straps 16, 17 and consequently, permitting the web binder anchors 47, as described above, to be tilted or angled by the spring 39 about the lugs or trunnions 27 to the position 35 shown in dotted lines in Figure 2. In this last-mentioned position the lug 46 on the anchor head of the now free end and still swinging strap anchor 18 will enter the recess 45, thereby locking the said strap anchor to the fixed member 42. 40 The previous engagement of the two webs will have operatively spliced the web of the expiring roll to that of the replacement roll so that the latter may serve as a continuation of the former after the web of the expiring roll is severed which is accomplished by any convenient means (not shown) almost simultaneously with the splicing of the two webs.

The present device provides certain operating advantages over the original invention as described and illustrated in the above-referred to Tomlin et al. applications in the way of smoother and more quiet operation, longer life and the quick stopping of the freed strap anchors which hitherto were prone to swing and oscillate for 55 sometime after the severing of the binder straps.

It will be understood that the invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

What I claim is:

1. The combination with means for confining the free end of a web roll to the body portion thereof while rotating, said means including adhesive straps and a strap anchor rotated with 70 the web roll; of other means effective upon the severance of said adhesive straps to lock the strap anchor against rotation.

2. The combination with means for confining the free end of a web roll to the body portion 75

thereof while rotating relatively to a support, said means including binder straps and a strap anchor; of an instrumentality connected to the support and other means secured to the strap anchor and coactable with said instrumentality for automatically locking the strap anchor thereto after the binder straps are severed.

3. The combination with a support for web rolls, means for confining the free end of a web roll to the body portion thereof while rotating relatively to the support, said means including adhesive straps pasted to the said free end and body portion, and strap anchors rotated with the web roll; of other means forming a part of said strap anchors and coactable with the support for preventing the rotation of the strap anchors after the straps have been disconnected from same.

4. The combination with a means for confining the free end of a web roll to the body portion thereof while rotating, said means including binder straps and an anchor for same; of other means forming a part of said anchor, and an instrumentality adapted to engage said other means for preventing the rotation of said anchor subsequently to the severing of said strap.

5. The combination with means for confining the free end of a web roll to the body portion thereof while rotating, said means including binder straps secured to said free end and to a strap engaging element; of means fastened to said strap engaging element, an anchorage non-rotatable relatively to said web roll and having a recess therein to receive said latter means for preventing the rotation of the strap engaging element subsequent to the severance of the straps, and spring means for biasing the strap engaging element and moving same so that the means thereon will enter the recess.

40 6. The combination with means for confining the free end of a web roll to the body portion thereof while rotating, said means including at least one pair of adhesive straps secured to the said free end and to members having means for fastening portions of said straps thereto; of abutments secured to said members, and means including non-rotatable elements having recesses adapted to receive said abutments for preventing the rotation of the members after the severance of the straps, said members being normally biased by springs.

7. The combination with means for confining the free end of a web roll to the body portion thereof while rotating, said means including adhesive straps and strap anchors rotated with the web roll; of an abutment projecting from said strap anchors, said abutment being receivable in a recess formed in a coacting anchorage, and resilient means for engaging the abutment with the anchorage after the adhesive straps have been severed.

8. The combination with means for confining the free end of a web roll to the body portion thereof while rotating, said means including adhesive tape connected to and between said free end and a strap anchor rotated with the web roll; of an abutment detachably mounted on and projecting from said strap anchor and coactable with means adapted to receive said abutment when said adhesive tape has been severed, and a spring effective for moving the strap anchor when same has been freed by severing the ad-

hesive tape, said strap anchor when moved, engaging the abutment with the said means.

9. The combination with means for confining the free end of a web roll to the body portion thereof while rotating, said means including adhesive straps and a strap anchor rotated with the web roll and about a fixed axis; of other means detachably secured to the strap anchor and removably insertable in a recess formed in a member secured to a fixed support, pivot means for permitting rocking of the strap anchor about an axis transverse to said first mentioned axis, and resilient means for biasing the strap anchor and moving same into the recess when the adhesive straps are severed.

10. The combination with means for confining the free end of a web roll to the body portion thereof while rotating, said means including adhesive straps and strap anchors rotated with the web roll; of other means including an element detachably mounted on each of said strap anchors and receivable in a recess formed in one of a plurality of coacting elements, one of said elements being fixed and another movable, and a spring normally maintaining a pressure upon each of said strap anchors, said spring moving an adjacent strap anchor and consequently the element on same into the said recess.

11. The combination with means for confining the free end of a web roll to the body portion thereof while rotating, said means including adhesive straps and a strap anchor rotated with the web roll; of a projecting abutment movably secured to the strap anchor, said abutment being removably insertable in a recess formed in coactable means, a spring engaged with said strap anchor and adapted to normally tilt same when not confined by said adhesive straps, whereby the projecting abutment will be received in said recess when said adhesive straps are severed.

12. The combination with means for confining the free end of a web roll to the body portion thereof while rotating, said means including adhesive straps connected to and between said free end and a strap anchor rotated with the web roll, and other means for preventing oscillation of the strap anchor after the adhesive straps are severed.

13. The combination with means for confining the free end of a web roll to the body portion thereof while rotating, said means including adhesive straps connected to and between said free end and a strap anchor rotated with the web roll, and other means for preventing oscillation of the strap anchor after the adhesive straps are severed, said last-mentioned means being movable about an axis transverse to that of the web roll.

14. The combination with means for confining the free end of a web roll to the body portion thereof for rotating; said means including a binder strap and a strap anchor rotated with the web roll; of other means effective upon the severance of said binder strap to lock the strap anchor against rotation.

15. In a web roll support, means rotatable with the roll and adapted to confine the free end of the web to the body of the roll and to release said free end, and a member effective to lock the said means against rotation when the free end is released.

HERMANN HEZEL.
